SPECIFICATION forming part of Design No. 23,617, dated September 4, 1894.

Application filed August 3, 1894. Serial No. 519,369. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of a number of wave lines representing water with figures of fish swimming, and seaweed, small balls or bubbles and crabs arranged irregularly over the wave or water lines as represented in the accompanying drawing.

The border or upper portion of the design is formed of similar wave or water lines with a scallop or wavy line of seaweed above the wa-

ter lines and a diamond net work with figures of swimming fish above the sea weed as shown in the drawing. A narrow band containing small ornaments forms the bottom of the border as shown.

What I claim is—

1. The design for wall paper herein shown and described.
2. In the design for wall paper the border herein shown and described.

Witness my hand this 31st day of July, 1894.

CHARLES BOOZE.
